UNITED STATES PATENT OFFICE.

HARLEY W. RUSS, OF HAVERHILL, MASSACHUSETTS, ASSIGNOR TO MERRIMACK WOOD HEEL CO., OF SALEM, NEW HAMPSHIRE, A CORPORATION OF MASSACHUSETTS.

WOOD-HEEL-SCOURING MACHINE.

Application filed February 20, 1924. Serial No. 694,166.

In the manufacture of wood heels, the operation of forming the sides of the heel, which is known as the "turning" operation, is performed by two rotary cutters which 5 are successively operated, on opposite sides thereof. In performing this operation, the cut is started at the breast surface, which has previously been formed by the so called "grooving" operation, and is continued on 10 each side to the middle of the back of the heel. While the surfaces formed by each cutter may be supposed to blend perfectly at this meeting point, as a matter of fact, principally on account of imperfect grind- 15 ing and setting of the cutter blades, they frequently do not blend, so that a shoulder, or a ridge or burr is usually formed or left at the point where the cutter which last operated finished its cut. While, theoreti- 20 cally, this shoulder ridge or burr will be left in the middle line of the back of the heel, yet in practice it is often left at a short distance to one side or the other of this middle line. The point at which the ir- 25 regularity is left depends largely on the operator, although a lot of heels turned by the same operator are usually the same in this respect.

It is usually necessary to blend these sur- 30 faces or remove this ridge or burr before the heel is covered, and this operation has usually been done by means of an ordinary cylindrical buffing roll. In performing this operation on the buffing roll, the operator 35 usually holds the heel in his fingers base down and moves the heel up or down while he holds the back of the heel against the roll. This operation, when performed in this manner, is frequently performed un- 40 satisfactorily, because the operator is liable to form a flattened surface on the back of the heel and is also liable, in performing this operation as rapidly as it is usually performed, to engage some other portion 45 of the heel than that which should be en- gaged to remove the ridge or burr or blend the surfaces, so that the intended operation will not be performed at all, this being partly due to carelessness and partly to the in- 50 ability of the operator to see whether he is performing the work correctly.

The objects of my invention are to pro- 55 vide an improvement in the art of scouring the back surfaces of a wood heel, whereby the operator may under ordinary conditions, by a single movement in one direction, blend the meeting surfaces formed by the turning operation, or remove any shoulder, ridge, or burr which may have been left as a result of such operation, whether at the middle back 60 line of the heel, or adjacent either side of such line, so that the formation of flat sur- 65 faces on the back of the heel may be avoided and the surfaces, when finished, will be rounded transversely thereof, and which will 70 enable the operator to perform the operation more rapidly than with the ordinary buffing roll and with less physical exertion.

I accomplish these objects in the manner 75 hereinafter described and illustrated in the accompanying drawings in which:

Fig. 1 is a front elevation of a machine embodying my invention and illustrating a preferred embodiment of my invention.

Fig. 2 is a side elevation of the abrasive 75 strip holder.

Fig. 3 is a plan view of the machine.

Fig. 4 is a detail view in perspective and partly in vertical section of a portion of the abrasive strip holder. 80

Fig. 5 is a detail view in horizontal sec- 85 tion illustrating the manner of engagement of the abrasive strip with the heel blank.

Fig. 6 is a perspective view of the abrasive strip holder.

Figs. 7 and 8 are detail sectional views 90 of the abrasive strip clamping means which I employ.

Fig. 9 is a detail view of one end of the holder. 95

As illustrated in the drawing, the machine may comprise any suitable form of frame 1, having a horizontal middle support 2 on which the heel blanks to be operated on may be readily placed and conveniently held in inverted position by any suitable means. Such means preferably comprises a base block 3, on which a flat metal plate 4 is secured and in which a side gage pin 5 is mounted, and breast gage block 6, which 100 is adapted to be clamped thereon in ad- justed position by means of a strap 7 and

clamping screw 8, so that the heel blank X may be held in position to be operated on, as hereinafter described.

I further provide a rectangular shaped bracket 10, which is connected at one edge by hinges 11 to the frame 1 to swing about a horizontal axis and two pairs of parallel links 12 and 14 are respectively connected at their lower ends by pivots 13 and 15 to the opposite edges of said bracket at directly opposite points, so that each link 12 swings about the same axis as the corresponding link 14. The upper ends of the links 12 and 14, at each end of the bracket 10 are pivotally connected in axial alignment by bolts 16, 17 respectively, to opposite sides of supporting blocks 18 and 19, and an adjusting rod 20 is rotatably mounted in said blocks at a short distance above the pivot bolts 16, 17. Cylindrically shaped clamp members 22, 24, of equal diameter are arranged on said rod in central alignment therewith at the adjacent sides of said blocks 18, 19, said rod having a right hand thread connection with one of said members 22 or 24, and a left hand thread connection with the other, so that when the rod is rotated in one direction, it will separate said members and when rotated in the opposite direction, it will move them towards each other, a handle 25 being provided on the rear end of the rod for the purpose of convenient adjustment. A pair of yokes 26, 28 are provided, one for each clamp member 22, 24, and the end portions of V-shaped round wire straps 27, 29 are secured in each yoke, the intermediate portion of each strap being bent semi-circularly to correspond to the curvature of the surfaces of the members 22, 24 and extending about the same. Clamping screws 30, 31 are threaded in the yokes 26, 28 and are arranged to be screwed against the clamp members 22, 24, so as to clamp the semi-circular portions of the straps against the opposite portion of the members. The portions of the holders which are engaged by the straps are preferably slightly grooved to receive said straps, as shown in Fig. 8. An oblong, relatively narrow flexible abrasive strip 32 of sand-paper, or similar material, is provided, of a width approximately equal to half the length of the circumference of the members 22, 24 and of a length sufficient to extend between said members, and the end portions of said strip are clamped against the semi-cylindrical faces of said members by means of the straps 27, 29 which are drawn thereagainst by means of the clamping screws 30. A pair of stiff rods 34, 36 are mounted at their ends in the yokes 26, 28 and extended therebetween in parallelism, the rod 34 being secured in the yoke 28 at one end and slidable at the other end 65 in the yoke 26 and the rod 36 being likewise

secured in the yoke 26 and slidable in the yoke 28, so that said rods act to hold the yokes in alignment and permit them to be moved to and from each other when the relative position of clamps are adjusted by means of the rod 20, to adjust the tension of the abrasive strip. Stop brackets 40, 41 are mounted on shelf 10 in position to limit the swinging movements of the links 12 and 14. 75

When the end portions of sand paper 32, are clamped against the faces of the members 22, 24, by the straps 27, 29, it is bent so that a transversely convex, or semi-cylindrical abrasive surface is provided, and as 80 the straps are arranged opposite the grooves formed in the members 22, 24, they will draw the strip portions which they engaged into said grooves, so that the strip will be securely attached. In practice, the tension 85 of the strip will be so adjusted by the rod 20 that it will bend inward to an extent when pressure is applied to the abrasive surface.

In using the device, the operator holds the heel on the plate 4 with his left hand, with one side against the pin 5 and the breast against the gage 6, which is so adjusted that the back portion of the heel base slightly overhangs or projects beyond the end of the plate 4, as shown in Figs. 1, 3, and 4. In this position the middle longitudinal line of the heel surface at its back will lie in a vertical plane which bisects the heel along said line and is perpendicular to the surface of the abrasive strip, so that, when the strip is moved into engagement with the surface of the heel, it will engage the same tangentially at said middle line and at right angles to said line. He also grasps the yoke 26 with his right hand, using it as a handle and draws it towards him so that the links 12 and 14 are in upright position, as shown in Figs. 2 and 6, in which position the rear end portion of the abrasive strip will be opposite the back of the heel. He then, or at the same time, swings the abrasive strip holder laterally towards the heel, this being permitted by the hinges 11, until the strip is engaged with the back of the heel at its top, as indicated in the dotted line position of Fig. 1. 100 He then pushes rearward on the yoke 26, so that the strip is drawn across the back of the heel and at the same time as the links are thrown rearward, it follows down the back of the heel to its base, blending the surfaces, or removing the ridge, or burr which may have been formed on the back thereof. As the links are of equal length and parallel, the action will be similar to that in a parallel ruler, as the abrasive strip will be supported in a horizontal position during the entire movement, and will be held against horizontal swinging movement from the tangential position with relation to the middle 105 of the back of the heel. 110

As the abrasive strip holder is moved downwardly and longitudinally, it will also be moved laterally according to the pitch or slope of the heel, this movement being permitted by the upward swinging movement of the bracket 10 on its hinges 11, and with a heel of the type illustrated, the bracket will be swung approximately from the declining position, shown in dotted lines 5 in Fig. 1, to a slightly upwardly inclined position, such as indicated in dotted lines in Fig. 6. This upward swinging motion of the bracket 10 is due to the supporting action of the downwardly inclined surface of the heel, as the strip holder is pushed longitudinally, the extent thereof depending on the pitch, or inclination of the back side of the heel.

The abrasive strip, therefore, is so supported that it has a free lateral movement, or a downward and sidewise movement in an oblique direction, according to the curvature and inclination, or longitudinal contour of the middle of the back surface of the heel, and at the same time, a longitudinal movement, while it is at all times held by its supporting means in a position which is approximately perpendicular to the vertical plane which bisects the heel along the middle longitudinal line of its back surface. As the holder which carries the abrasive strip is necessarily of substantial weight, and as the heel, when held in position to be operated on, is held in an inverted position, 25 so that the entire, or practically the entire back surface, which is engaged by the strip, faces upward and declines from the top to the base of the heel towards the strip, the greater portion of the weight of the holder will be supported by the heel. That is, the gravity of the holder materially assists the operator in pressing the abrasive strip against the heel, so that when performing the operation, his strength will 40 be largely exerted in pushing the holder from him, as the strip follows along down the back of the heel. Moreover, the arrangement is such that the operator may press downward on the holder, as he pushes it 45 from him without particular effort, so that the operation may be performed with slight physical exertion.

The purpose of clamping the heel on the flat metal plate 4 in such a position that its back portion projects beyond the edge of the plate is to enable the abrasive strip to operate on the back surface of the heel throughout its entire length and to prevent engagement of the strip with any portion of the machine at any time during the operation. To avoid such engagement, the plate 4, which is thin, is projected to an extent beyond the frame portion on which it rests. With this arrangement, as the operator finishes his stroke, the abrasive strip, with

its holder, merely swings into space, as it becomes disengaged from the heel and its forward and downward movement will ordinarily be arrested by the operator, who then draws it back to its initial position.

While the heel will usually be so positioned on its support that the ridge on its back, which is to be removed, will be engaged by the abrasive surface when the longitudinal lines of said surface are straight, it 70 will frequently occur that the ridge will be at one side or the other of such a position. For this reason, the longitudinal tension on the abrasive strip will be so adjusted that, when the strip is pressed against the back of the heel, it will yield sufficiently to permit the strip to be wrapped about the heel transversely to a sufficient extent to embrace, or engage all the surface portion in which the ridge would be likely to be located, as indicated in Fig. 5. As the strip is carried over the surface, it will not only engage the ridge wherever it is located, within certain limits, but will also have a rounding action transversely of the heel, so that the formation of 80 flattened surfaces on the back of the heel, as often occurs when the buffing roll is used, will be avoided.

It will also be noted that, as the flexible strip is supported so that it is somewhat 85 yieldable, it will conform perfectly to the longitudinal configuration of the heel, as well as to its transverse curvature, as shown in Fig. 4. As a result, the ridge or burr on the back of the heel will not only be removed, but the meeting surfaces, formed by the two cutters, will be practically perfectly blended. As the holder may be moved rotatably in the bearing blocks 18, 19, the operator is enabled to engage practically all portions of 90 the abrasive surface between the clamp with the work. The operation is rapid, as, usually, it is only necessary to draw the abrasive strip across the heel once.

I claim:

1. That improvement in the art of scouring the transversely convex back surface of a wood heel which consists in holding the heel in a predetermined position, so that its back surface may be conveniently operated on, 115 supporting an elongated flexible abrasive strip at its ends, so that its intermediate portion will be so tensioned that it may be conformed to said surface transversely and longitudinally, positively holding the strip approximately perpendicularly to the plane which bisects the heel along the middle longitudinal line of its back surface and then moving the strip longitudinally and transversely while it is held in said perpendicular relation and engaged with said surface.

2. That improvement in the art of scouring the transversely convex back surface of a wood heel which consists in holding a heel so that its back surface faces upward, sup-

porting an elongated flexible abrasive strip at its ends, so that its intermediate portion will be so tensioned that it may be conformed to said surface transversely and longitudinally, positively holding the strip approximately perpendicularly to the plane which bisects the heel along the middle longitudinal line of its back surface and then moving the strip longitudinally and at the same time transversely, while it is positively held in said perpendicular relation and engaged with said surface.

3. That improvement in the art of scouring the transversely convex back surface of a wood heel which consists in holding a heel in an inverted position so that its back surface faces upward and extends obliquely downward from top to base, supporting an elongated flexible abrasive strip at its ends, so that its intermediate portion will be so tensioned that it may be conformed to said surface transversely and longitudinally, positively holding the strip in all positions thereof approximately perpendicularly to the plane which bisects the heel along the middle longitudinal line of its back surface and then manually moving the strip longitudinally transversely and downwardly according to the inclination of said back line, while engaged with said surface and while held in said perpendicular relation.

4. That improvement in the art of scouring the transversely convex back surface of a wood heel which consists in holding a heel in an inverted position so that its back surface faces upward and extends obliquely downward from top to base, supporting an elongated flexible abrasive strip at its ends by a holder of substantial weight, so that its intermediate portion may be conformed to said surface transversely and longitudinally, supporting such holder in position constantly to hold the strip approximately perpendicularly to the plane which bisects the heel along the middle longitudinal line of its back surface and to permit free manual and gravity actuation thereof, and then manually moving the holder to move the strip longitudinally and downwardly in an oblique direction, according to the inclination of said line, while it is held in said perpendicular relation and pressed by the gravity of the holder against said surface.

5. That improvement in the art of scouring the transversely convex back surface of a wood heel which consists in holding a heel so that its back surface faces upward, supporting an elongated flexible abrasive strip at its ends, so that it has a transversely convex abrasive surface throughout its length and its intermediate portion is loosely supported to permit it to be conformed to the transverse and longitudinal curvature of the back surface of the heel, positively holding the strip approximately perpendicularly to the

plane which bisects the heel along the middle longitudinal line of its back surface, and then causing the strip to have a combined longitudinal and transverse movement while held in said perpendicular relation and moved from end to end of said surface while engaged therewith.

6. That improvement in the art of scouring the transversely convex and longitudinally curved back surface of a wood heel which consists in so supporting the heel in a fixed inverted position, so that its back surface extends obliquely downward from top to base and a free space is provided below and at one side of said surface, supporting an elongated, flexibly abrasive strip at its ends, by a holder of substantial weight, so that the intermediate portion of the strip may be conformed to said surface transversely and longitudinally and so that the strip will be constantly held approximately perpendicularly to the vertical plane which bisects the heel along the middle longitudinal line of its back surface, and manual and gravity action of said strip will be permitted to carry the same longitudinally and at the same time obliquely downward into said open space while engaged with said surface.

7. A machine for scouring a transversely rounded and longitudinally curved surface comprising means for holding the work with its longitudinal lines in a vertical position, a relatively narrow flexible abrasive strip, a support therefor mounted to swing about a horizontal axis, a pair of parallel links pivotally mounted at their lower ends on said support, two pairs of clamp members one member of each of which is pivotally connected to the upper end of one of said links and has a clamping face at one side, said faces being arranged in horizontal alignment to engage the back side of the opposite end portions of said strip, to hold the latter horizontally in transverse engagement with the surface of the work on said holding means and means for rigidly connecting said members having adjusting means for varying the proximity of said members to vary the tension of the strip held thereby, the other clamp members being arranged to clamp said strip end portions against said faces to conform the same thereto.

8. A machine for scouring a transversely rounded and longitudinally curved surface comprising a work support, a relatively long and narrow strip of flexible abrasive material, a holder therefor comprising two pairs of clamp members, each having one of the members thereof provided with side faces, and having means for constantly holding the same with their faces in alignment to receive the back side of the end portions of the strip, means for moving the other clamp members to clamp the strip against said faces, means combined with the holding

means of said members permitting relative adjustment of said clamps to vary the tension of the strip as it extends therebetween, means for holding said members against relative lateral displacement from their aligned positions in the different positions of adjustment thereof, to prevent movement of the end portions of the strip out of line, and means for supporting said holder permitting said strip to be manually moved longitudinally and laterally in transverse relation to the work on said support.

9. A machine for scouring a transversely rounded and longitudinally curved surface, comprising a work support, a holder for a flexible abrasive strip comprising two pairs of clamp members, one member of each clamp having a cylindrical face for receiving the back side of the end portions of the strip, said faces being of equal diameter and arranged in axial alignment, and the other members of said clamps being adapted to clamp said strip end portions against said faces to bend the strip into semi-cylindrical form, means for rigidly connecting said cylindrical clamp members, and supporting means therefor arranged to permit rotational movement thereof about their axes, said supporting means being arranged to carry said strip longitudinally and permit simultaneous lateral movement thereof.

10. In a wood heel scouring machine, a frame having a heel support, a holder for a strip of flexible abrasive material comprising two pairs of clamp members, a rod having one member of each clamp mounted for relative adjustment thereon, a slidable connection between said adjustably mounted members for holding them in alignment in their different positions of adjustment, a pair of holding blocks in which the opposite end portions of said rod are mounted and a pair of parallel links pivotally connected at corresponding ends to said frame and at their opposite ends to said holding blocks respectively.

11. In a wood heel scouring machine, a heel support, a holder for a strip of flexible abrasive material comprising two correspondingly formed clamp members, a rod on which said members are mounted and arranged for relative adjustment longitudinally thereof, said members each having a cylindrical face concentrically arranged with relation to the rod, means for clamping the abrasive strip against said faces to hold the strip in semi-cylindrical form, supporting blocks in which said rod is rotatably mounted and means for supporting said block to permit simultaneous longitudinal and transverse movement of the holder in operative relation with said heel support.

12. In a wood heel scouring machine, a heel support, a holder for a strip of flexible abrasive material comprising a pair of clamp

members having cylindrically formed faces, a rod on which said members are mounted, and arranged in central alignment and for adjustment longitudinally thereof, a yoke for each clamp member having a strap arranged to extend about the face thereof and having means engaging the member for clamping the strip therebetween, means extending between said yokes for holding them in alignment and arranged to permit relative adjustment of said members when in clamped position, and supporting means for said members arranged to permit combined longitudinal and lateral movement in operative relation to said heel support.

13. In a wood heel scouring machine a heel support, a holder for a strip of flexible abrasive material comprising a pair of clamp members having cylindrically formed faces, a rod on which said members are mounted and arranged in central alignment and for adjustment longitudinally thereof, a yoke for each clamp member having a strap arranged to extend about the face thereof and having means engaging the member for clamping the strip therebetween, means for holding said members against relative rotational movement and supporting means connected to said rod and arranged to permit compound longitudinal and transverse movement thereof when the strip is held in operative relation to said heel support.

14. A machine for scouring the transversely convex back surface of a heel, comprising a horizontally disposed support adapted to receive the heel base and hold the heel in inverted position, means for positioning the heel on said support so that one end of the support is disposed within the edge of the middle back portion of the heel base, an elongated abrasive strip, and means arranged to hold said strip in a position approximately perpendicular to the plane which bisects the heel along the middle line of its back surface, when positioned on said support, and manually movable to engage the strip with said surface and carry it longitudinally and at the same time laterally, according to the longitudinal contour of said surface and downwardly opposite said end of said support, while the strip is held in said perpendicular relation.

15. A machine for scouring the transversely convex back surface of a heel, comprising a horizontally disposed support adapted to receive the heel base and hold the heel in inverted position thereon, means arranged to engage one side and the breast of the heel, to position the heel on said support so that one end of the support is disposed within the edge of the middle back portion of the heel base, an elongated abrasive strip and means arranged to hold said strip in a position approximately perpendicular to a vertical plane which bisects the heel along

the middle line of its back surface when positioned on said support, and manually movable to engage the strip with said surface and carry it longitudinally and at the same time laterally according to the longitudinal contour of the surface and downwardly, opposite the end of said support,

to operate on said surface throughout its entire length while the strip is held in said perpendicular relation.

10

In testimony whereof, I have signed my name to this specification.

HARLEY W. RUSS.
